UNITED STATES PATENT OFFICE.

GEORG THOMAS, OF BRESLAU, GERMANY.

SPARK-ARRESTER.

1,118,452.

Specification of Letters Patent. Patented Nov. 24, 1914.

Application filed August 16, 1913. Serial No. 785,168.

To all whom it may concern:

Be it known that I, GEORG THOMAS, a subject of the King of Prussia, German Emperor, residing at Breslau, in the Kingdom of Prussia, German Empire, have invented 5 certain new and useful Improvements in Spark-Arresters, of which the following is a specification.

The spark arresters arranged in the smoke 10 box of the engine present the inconvenience that they often get clogged by the deposit formed of the solid particles and of the tarry substances separating from the gases of combustion. In order to obviate this inconvenience the spark arrester according to this invention is not fixed to the wall of the smoke 15 box or to the chimney or to the conical head of the steam pipe, but loosely mounted in a frame which is arranged in said smoke box. 20 The spark arrester is thus continuously shaken when the engine works so that a clogging of the spark arrester is effectually prevented.

There have already become known spark 25 arresters with movable baskets but these baskets are not rigid so that the vibrations and shocks from the engine are only incompletely transferred to the movable parts of said spark arresters.

According to this invention the spark arrester comprises one or more baskets, which 30 are completely rigid and loosely mounted in a frame so that the shocks are thoroughly transmitted with full strength to the spark 35 arrester so that a clogging of the same is absolutely prevented.

In the accompanying drawings a spark arrester comprising two baskets is shown by way of example.

Figure 1 is a longitudinal section. Figs. 2 and 3 are perspective views.

The spark arrester is mounted as usual between the chimney 2 and the conical head 3 of the steam pipe 4 and it consists of two 45 separate baskets 5 and 6 of the shape of a hollow rigid inverted pyramid, the walls of which are made of fixed and inclined small plates. Upon the outwardly bent flange 2' of the chimney, bars 7 are fixed which carry 50 a rectangular plate 8 carrying by means of vertical bolts 9 lower plate 11 which has at the middle a circular aperture 10. The two plates form the frame for the upper part 5 of the spark arrester. The distance between 55 the two plates 8 and 11 is greater than the height of the spark arrester and the distance

between the vertical bolts 9 is greater than the width of said spark arrester so that the same can freely move in vertical and lateral directions. The lower part 6 of the spark 60 arrester is situated under the plate 11 and has lateral flaps 12 which engage with U-irons 13 fixed upon a plate 14 which is mounted with a central opening upon the flange 15 of the cone-shaped head 3 of the 65 steam pipe and sits loosely upon the flange 16 of said steam pipe 4. The plate 14 has an upwardly inclined part 17 which serves as abutment for the spark arrester if the same moves in the U-shaped rails 13 in the direction of the arrow (Fig. 1). Studs 18 downwardly projecting from the plate 11 serve for limiting the displacement of the spark arrester in the other direction.

The distance between the plates 11 and 14 75 is greater than the height of the lower part of the spark arrester and the distance between the abutment plate 17 and the studs 18 is greater than the length of said part 6 of the spark arrester. The two parts 5 and 6 80 of the spark arrester being loosely mounted in the frames (the frame for the lower spark arrester consists of the parts 16, 17, 18 and 11) can freely move in vertical and lateral directions and jump continuously owing to 85 the vibrations of the engine, whereby the clogging of the apparatus is absolutely prevented. As the upper part 5 of the spark arrester has to do more work than the lower part 6 it is arranged so that it can also turn 90 around its axis. The spark arrester can be removed from the smoke box after the front bolt 9 has been loosened. For removing the lower part 6 of the spark arrester the studs 18 have to be lifted. The rear wall of the 95 lower part 6 of the spark arrester has an opening 19 (Figs. 2 and 3) so that, when this part is pulled out of the frame its movement is not impeded by the conical head 3 of the steam pipe 4.

I claim:—

A spark arrester comprising in combination a plate securely fixed to the chimney projecting into the smoke box, vertical bolts in said plate, a lower plate fixed to the lower 105 ends of said vertical bolts, an upper rigid spark arrester-basket loosely mounted upon said lower plate so that it can freely move in vertical and in lateral directions, a lower rigid spark arrester-basket having an opening 110 in one side, flaps at the longitudinal sides of said lower rigid spark arrester-basket, a

base plate mounted at a distance below the lower plate of the upper spark-arrester-basket which is greater than the height of said lower spark arrester-basket, longitudinal
5 rails fixed upon said base plate designed to receive the flaps of the lower spark arrester-basket, an upwardly inclined abutment plate at one end of the base plate, and studs downwardly projecting from the lower plate at
10 the side opposite said abutment plate and at

a distance from said abutment plate which is greater than the length of the lower spark arrester-basket substantially as described and shown and for the purpose set forth.

In witness whereof I have hereunto set 15
my hand in the presence of two witnesses.

GEORG THOMAS.
